UNITED STATES PATENT OFFICE.

WILLIAM ARTHUR JONES, OF MANCHESTER, ENGLAND, ASSIGNOR TO SONJE LIMITED, OF MANCHESTER, ENGLAND, A COMPANY OF THE UNITED KINGDOM OF GREAT BRITAIN AND IRELAND.

SPARKING PLUG.

1,426,333.

Specification of Letters Patent. Patented Aug. 15, 1922.

Application filed December 7, 1920. Serial No. 428,994.

(GRANTED UNDER THE PROVISIONS OF THE ACT OF MARCH 3, 1921, 41 STAT. L., 1313.)

To all whom it may concern:

Be it known that I, WILLIAM ARTHUR JONES, a subject of the King of Great Britain and Ireland, and a resident of 5 Urmston, Manchester, in the county of Lancaster, England, have invented certain new and useful Improvements in Sparking Plugs (for which I have filed an application in Great Britain Aug. 6th, 1919, Ser. 10 No. 19358), of which the following is a specification.

This invention relates to sparking plugs for electrical ignition systems, and to 15 sparking plugs of the kind in which the negative electrode or electrodes is or are mounted on the inner end of, and removable from the outer casing or plug body with, the insulating body which carries the positive electrode. An object of the invention 20 is to provide an improved arrangement for mounting and securing the negative electrode or electrodes on said insulating body whereby the construction of sparking plugs is simplified and efficient electrical connection 25 between the negative electrode or electrodes and the outer casing or plug body is ensured.

According to this invention, the negative electrode or electrodes is or are mounted 30 and secured on the insulating body which carries the positive electrode, by or through the medium of a ring or washer of conducting material which is a tight fit on the insulating body against an abutment there- 35 on and which is clamped between said abutment and a complementary internal annular seat on the outer casing or plug body when the insulating body is fitted and secured therein.

40 In the accompanying drawings, which illustrate one embodiment of the invention, Fig. 1 is an elevation of the sparking plug with the plug body and cap or gland in section. Fig. 2 illustrates the insulating body removed from the plug body and as viewed from the left hand side of Fig. 1, and Figs. 3 and 4 are elevations at right angles to each other. Fig. 4 being partly in section, of the inner end of the insulating body, to an enlarged scale, and Fig. 5 a 45 sectional plan taken on the line 5—5 of Fig. 4.

The insulating body *a* carrying a central positive electrode *b* also carries a negative

electrode *c* which is attached to the insulating body *a* by a ring or washer *d*.

The free end *c*¹ of the negative electrode *c* is appropriately shaped to form the complementary sparking point to the inner end *b* of the positive electrode *b*. The other end *c*² of the negative electrode *c* is bent at right angles and is secured by being clamped between the said ring or washer *d* and a shouldered or enlarged portion *e* of the insulating body *a*, the enlarged portion *e* being formed with a recess *f* for receiving the bent end portion *c*². The recess may be formed in the enlarged portion by pressing the bent end *c*² of the negative electrode *c* into the same, such as by pressure applied to the ring or washer *d*, which is made so as to be a tight fit on the part *g* of the insulating body. The part *g* of the insulating body *a* is formed with a lengthwise groove *h*, to receive the stem of 75 the electrode *c*. The sparking end *b*¹ of the positive electrode *b* may be cut away on the side facing the negative electrode, as at *b*², if found necessary, to ensure sparking taking place between the end *b*¹ of the positive electrode and the end *c*¹ of the negative electrode *c*, and not between the stem of the negative electrode and the end of the positive electrode.

From the above description, it will be 85 understood that the negative and positive electrodes and insulating body are firmly connected and are removable from the plug body *j* in one piece for cleaning, inspection and other purposes, without the possibility 90 of any of the parts becoming disconnected or lost, or the insulating body being fitted into the plug body with the electrodes out of their proper positions relatively to each other.

95 Although only one embodiment of the invention has been described and illustrated, it will be obvious that various modifications may be devised without departing from the spirit of the invention.

The insulating body constructed as above with the positive and negative electrodes attached thereto, is arranged in the plug body *j* with the ring or washer *d* resting on the internal annular seat *j*¹ thereof, and 105 is secured in position by a gland nut *k* which engages with the plug body *j* and bears on a washer *l* fitted on the insulating

body against the upper annular surface of the enlargement *e*.

What I claim as my invention, and desire to secure by Letters Patent is:—

5 1. A sparking plug comprising an insulating body provided with an abutment, an electrode mounted in said body, a complementary electrode mounted on said body, a ring or washer of conducting material 10 separate from the complementary electrode and tightly fitting on said body against said abutment and securing said complementary electrode to said body to form a unit therewith, an outer casing in which said insulating body is fitted and provided with an internal abutment against which said ring or washer bears, and means for securing said body on said casing.

2. A sparking plug comprising an insulating body provided with an abutment and formed with a groove in the exterior surface of its inner end, a positive electrode mounted in said insulating body, a complementary electrode mounted in said groove, 25 a ring or washer of conducting material separate from the complementary electrode and forced on said insulating body to en-

gage said abutment and secure said complementary electrode in said groove, an outer casing in which said insulating body is fitted having an internal abutment against which said ring or washer bears, and means for securing said insulating body in said outer casing.

3. A sparking plug comprising an insulating body formed with a groove in the exterior surface of its inner end and provided with an abutment formed with a recess, a positive electrode mounted in said insulating body, a negative electrode 40 mounted in said groove and having one end lying in said recess, a ring or washer of conducting material fixed on said insulating body in engagement with said abutment and securing said negative electrode, 45 an outer casing in which said insulating body is mounted and provided with an internal abutment against which said ring or washer bears, and means for securing said insulating body in said casing.

In witness whereof I have hereunto set my hand.

WILLIAM ARTHUR JONES.
